UNITED STATES PATENT OFFICE.

EBENEZER HILL, JR., OF SOUTH NORWALK, CONNECTICUT.

IMPROVEMENT IN STEAM-PUMPS.

Specification forming part of Letters Patent No. 174,955, dated March 21, 1876; application filed February 15, 1876.

To all whom it may concern:

Be it known that I, EBENEZER HILL, Jr., of South Norwalk, in the county of Fairfield and State of Connecticut, have invented certain new and useful Improvements in Steam-Pumps; and I do hereby declare that the following is a full, clear, and exact description thereof, which will enable others skilled in the art to which it pertains to make and use the same, reference being had to the accompanying drawings, and to the letters of reference marked thereon, which form a part of this specification.

This invention relates to that class of pumping engines known to the art as compound or differential cylinder-pumps; and my invention consists in arranging within the main cylinder of a double-acting pump an auxiliary cylinder-piston of novel construction, in which the ports or conduits are so located in the main cylinder, as well as in the auxiliary cylinder, as to register at a certain point of its stroke, due regard being had to the stroke of the operating-engine and the cut-off of the steam, whereby the power exerted on the piston of the steam-engine at the termination of its stroke is lessened, and particularly when working expansively, and, as is well known, the power of which is considerably reduced at the end of its stroke, which will be more fully hereinafter explained. It also consists in providing a pump with a piston within the auxiliary cylinder, and its peculiar arrangement of induction and ejection valves and ports, whereby with a uniform expenditure of power will produce a higher pressure of water at the end of the stroke of the pump than at the beginning. In a special manner is this useful when a cut-off valve is applied to the driving-engine.

Referring to the accompanying drawing, which represents a longitudinal vertical section of a double-acting pump, the valves shown being common clack-valves, although others may be employed, if desired—

In the drawing, A is the main cylinder of a double-acting pump, S S', and R and R' are suction and discharge valves within the cylinder A. C is the auxiliary cylinder, which is made to fit in the cylinder A by turning and packing in the manner of a piston. This cyl-

inder C is also bored out in the usual manner, and has fitted within it a piston, E, which is attached to its operating piston-rod F, which passes through the cylinder-head of C, and also of cylinder A, and is connected to any suitable power for operating the pump, generally to the steam-piston of a direct-acting engine. The cylinder C has induction and ejection ports D' D' and D D at each end, registering with ports P P and P' P' longitudinally arranged in cylinder A.

It will be observed that these ports extend into the cylinder beyond the clack-valve ports, the purpose of which is to form a communication with the ports of cylinder C before said cylinder reaches the end of its stroke, thus avoiding any sudden jar or thump of the working parts on relieving the pump of its load.

The operation of my improved pump is as follows: The cylinders A and C are well charged with water. The power being applied to move piston E by means of piston-rod F in the direction of the arrow, the action will be to cause piston E to press upon the water in cylinder C, which has been supplied through the auxiliary valve V. Thus, during the main portion of the stroke, no opening is provided for the water to escape from cylinder C, so the water becomes practically a solid body, and forming a piston, moving the whole of the cylinder C forward by the power of piston E, cylinder C becoming a piston for cylinder A. On reaching ports P a quantity of water is discharged, due to the extended diameter of C. This action will continue until the port B of cylinder C has passed the ports P, and the ports D of cylinder C will register and communicate with said ports P of cylinder A. Cylinder C will then cease to move, and piston E continuing its motion within it will discharge the water due to the area of F. However, it will be observed that the internal diameter of C is less than the internal diameter of A; hence the piston E encounters less resistance to its movement than when moving the whole cylinder C. Thus it will be seen that should the steam be cut off at the point where ports D register with ports P, the expanding steam in the steam-cylinder will be sufficiently powerful to complete the stroke of piston E in the pump. Through the valve V and ports D' D'

water fills the cylinder C behind the piston E, when the return stroke is the same as the advance.

It will be seen from the foregoing that a greater water-pressure takes place at the end of the stroke than at the beginning, thus fully filling the duty required when used for force-pumps or air-compressors.

Having thus fully described my invention, what I claim as new, and desire to secure by Letters Patent, is—

1. The combination of auxiliary piston-cylinder C, piston E, main cylinder A, valve V, all co-operating to produce the result substantially as described.

2. The combination, in a steam-pump, of main cylinder A, auxiliary cylinder C, piston E with its operating rod passing through both cylinder-heads, with ports D D and D' D', P P and P' P', and valve V, all constructed and arranged to operate in the manner and for the purpose set forth.

In testimony that I claim the foregoing as my own invention I affix my signature in the presence of two witnesses.

EBENEZER HILL, JR.
